UNITED STATES PATENT OFFICE.

WELLS ELY SERGEANT, OF MINNEAPOLIS, MINNESOTA.

MACHINE FOR DEGERMINATING AND SCOURING WHEAT.

SPECIFICATION forming part of Letters Patent No. 309,574, dated December 23, 1884.

Application filed March 1, 1884. (No model.)

To all whom it may concern:

Be it known that I, WELLS E. SERGEANT, of Minneapolis, Hennepin county, Minnesota, have invented certain new and useful Improvements in Machines for Degerminating and Scouring Wheat, of which the following is a specification.

Wheat-kernels in their natural condition carry at one end what is commonly known in the art as the "germ," and at the opposite end a light fuzzy portion, both of which must be removed before the reduction of the grain, in order that they may be successfully separated therefrom. The body of the kernels is also enveloped in an external jacket, commonly known as the "husk" or "bran," which must be left as nearly as possible in its original condition—that is to say, continuous and of full strength and thickness up to the time of the first reduction, in order that it may be loosened thereby in large pieces adapted for ready and successful separation.

It is the purpose of my machine to effectually remove the germ and fuzzy matters without reducing the thickness or strength of the bran and without fracturing either the bran or the outer portion of the berry. To this end it relates to a machine composed, essentially, of horizontal disks revolving within a body provided with internal flanges which overlap the edges of the disks, the invention consisting in the construction and combination of the parts, hereinafter specified and claimed in detail.

The machine may be constructed with a single shaft provided with disks, or with two or more such shafts, so arranged that the disks of one will enter between those of another.

Referring to the accompanying drawings, Figure 1 is a vertical section of my machine in its preferred form, with two shafts provided with disks, the section being taken on the line *x x* of Fig. 2. Fig. 2 is a horizontal section on the line *y y* of Fig. 1, the driving-pulleys and belt being represented in dotted lines. Fig. 3 is a vertical cross-section on the line *z z* of Fig. 2. Fig. 4 is a horizontal section of the machine as constructed with a single shaft and series of disks.

A represents an upright rigid frame provided at its upper and lower ends with bearings to sustain two upright shafts, *B* and *B'*. The bearings in which the lower ends of the

shafts are stepped are adjustable vertically in a bridge-tree or support, *D*, and sustained by means of hand-screws *E*, commonly known in the art as "tempering" screws, by means of which the bearings and shafts may be raised and lowered, as required. In place of the screws other equivalent means may be employed to adjust the shafts vertically.

On each of the shafts I secure at suitable distances apart a series of horizontal disks, *F*, each of which has its upper surface ribbed, toothed, or otherwise formed to cause an abrasive action on the ends of the grain. Each disk is provided on the under side with a number of peripheral depending studs, *a*, preferably made of the sectional form represented by dotted lines in Fig. 2—that is to say, with their inner vertical surfaces inclined from the edges toward the center of the disk. The shafts are separated a distance slightly greater than the diameters of the disks, which are so arranged that those of one shaft revolve between the edges of those on the opposite shaft, as plainly represented.

Within the main frame I secure an upright perforated jacket or casing, *G*, which follows the outer edges or margins of the disks at a distance ordinarily of about three-fourths of an inch therefrom. This jacket serves to retard the passage of the grain and to confine the same subject to the action of the disks. Against the inner surface of the perforated jacket, I secure a series of horizontal flanges or rings, *H*, the inner edges of which overhang the edges of the disks in the manner represented in Figs. 1 and 2. These rings serve as scouring-surfaces to act upon the ends of the grain, and also as a means of causing the grain to flow inward and outward in passing from one disk to the next. Around the perforated jacket I arrange a closed body or jacket, *I*, leaving between the two a space of about one inch, more or less, into which the air is freely admitted through openings *J* at the lower end. This space is designed to receive dust and light impurities which may escape through the perforated jacket, and it communicates at the top, through a suitable opening, with a casing containing a suction-fan, *K*, applied to the upper end of the shaft *B*, or otherwise suitably driven.

Grain is introduced into the machine through

a feed-spout, L, at the top, as represented in Fig. 1, and is delivered through a spout, M, extending downward from the interior, as represented in Fig. 3. The delivery-spout dis- 5 charges into an air flue or duct, N, the lower end of which is open, while the upper end communicates with the fan case or chamber, as represented in Fig. 3. The upper end of the suction-flue communicates at one side with a 10 top of a hopper or receptacle, O, closed at the lower end by a gravitating valve, P. The upper end of this hopper also communicates by an independent passage, Q, with the atmosphere, this passage being provided with 15 a valve, R, by which it may be wholly or partially closed.

The operation of the machine is as follows: The parts being set in motion, a strong draft is created upward through the space surround- 20 ing the perforated jacket, and also through the duct with which the grain-delivery spout connects, as well as through the passage Q from the top of the hopper. The grain, being introduced at the top, encounters the upper 25 surfaces of the top flange and disk. It is carried outward by the motion of the disk in all directions, and passes over the edge of the disk between its upper surface and the under surface of the flange above, and thence down- 30 ward past the edge of the disk toward the flange and disk next below. As the grain passes the periphery of the disk it is acted upon by the depending studs, which have the effect of throwing it toward the center and of equaliz- 35 ing its distribution. Pursuing its downward course the grain travels alternately inward and outward, being thrown inward by the upper surfaces of the flanges, and outward by the upper surfaces of the disks, so as to pass down- 40 ward beneath the flanges.

In the double machine, such as above de- 45 scribed, the grain is subjected to the action of the disks of the two shafts alternately. Reaching the foot of the machine the grain escapes through the delivery-pipe into the passage or 50 duct, where it meets the ascending air-current, by which the fuzzy matters and light impuri- ties are carried upward.

While it is preferred to construct the ma- 55 chine with two shafts, as above described, it may be constructed, as shown in Fig. 4, with a single shaft provided with disks, in which case the body or inclosing jacket is made of cylind- 60 rical form, and the internal flanges adapted to encircle the shaft, as shown. In other respects the machine is identical in construction and mode of operation with the first described.

I am aware that machines have been con- 65 structed in a great variety of forms with re- volving disks and cones with flanges overhang- 70 ing the disks.

It will be observed that the teeth or ribs are arranged on the disks in oblique or radial lines, or, in other words, their outer ends carried forward. By this arrangement they are caused 65 to assist in retarding the grain until the clean- 75 ing action is fully completed.

I am aware that scouring-machines have been constructed in which disks were revolved above annular flanges underlying their outer 70 edges; also, that a shaft has been provided with a series of disks, one above another, encircled by a body having annular flanges which pro- jected inward between the under surface of one disk and the upper surface of the next, and 75 to such construction I lay no broad claim.

Having thus described my invention, what I claim is—

1. In a wheat-scouring machine, two vertical shafts, provided with overlapping scouring- 80 disks, in combination with a surrounding case or jacket, and the internal flanges, whereby the grain is caused to pass over the surfaces of all the disks in succession.

2. The combination of the two upright shafts, 85 the scouring-disks mounted thereon, the encir- cing-jacket in the form of two cylindrical seg- ments, and the segmental flanges attached to the inner surface of the jacket and overlap- 90 ping the respective disks.

3. The two upright shafts and their over- 95 lapsing disks, in combination with the upright perforated jacket encircling the disks, as shown and described, the close body encircling the jacket, and the fan arranged to produce a draft outward through the jacket from all sides, as shown.

4. In a wheat-scouring machine, rotary 100 scouring-disks having depending peripheral studs, substantially such as shown and de- scribed, in combination with an encircling- 105 jacket, having flanges extended inward over the edges of the disks, substantially as de- scribed and shown.

5. In a machine for removing the end por- 110 tions of the wheat-berry, the combination of a series of horizontal revolving disks, a perfo- rated jacket inclosing the same, flanges ex- tending inward from the jacket and overlap- 115 ping the edges of the disks, an impervious body surrounding the jacket, a wheat-spout at the base, a hopper, O, at the top, an air passage or conductor connecting said hopper with the delivery-spout, and an exhaust-fan communi- cating with the hopper, the air-passage, and the space around the perforated jacket, and arranged to produce an upward draft, as de- 120 scribed and shown.

WELLS ELY SERGEANT.
